UNITED STATES PATENT OFFICE.

LEOPOLD FEUERSTEIN, OF CHICAGO, ILLINOIS.

CLOCK.

SPECIFICATION forming part of Letters Patent No. 352,303, dated November 9, 1886.

Application filed October 23, 1885. Serial No. 180,724. (No model.)

To all whom it may concern:

Be it known that I, LEOPOLD FEUERSTEIN, a citizen of the United States, residing at Chicago, in the county of Cook and State of Illinois, have invented certain new and useful Improvements in Clocks; and I hereby declare the following to be a full, clear, and exact description of the same.

My improvement relates particularly to pendulum-clocks.

The object of my invention is to afford a device which shall serve as an accessory attachment to the ordinary forms of pendulum-clocks, by which an observer shall be enabled to determine at a glance whether or not the clock is "going," and which shall afford an attractive appearance to the dial and clock-face; and it is further my object to accomplish the foregoing ends by means simple and inexpensive in construction.

My invention consists in the general construction of my improved device, and also in certain details of construction and combinations of parts forming the same, and comprising a figure or figures upon or about the dial, and having eyes movable by means of certain mechanism connected with the pendulum, by which, when the latter is in motion, the eyes will continue a rolling movement within their sockets, and thus indicate that the clock is running.

Referring to the drawings, Figure 1 is a rear elevation of a clock having works provided with my improved attachment; Fig. 2, a sectional plan view taken on the line 2 2 of Fig. 1; Fig. 3, a vertical sectional side elevation; and Fig. 4, a perspective view of an eyeball, showing the manner of pivoting and actuating the same.

A is a clock-casing, commonly formed of wood, and provided with a clock-movement, B, of common construction. To the upper portion of the frame of the clock-movement B is secured an arch-shaped projection, C, from the top of which, at the center t, is hung a pendulum, D, controlled by an anchor-escapement, E, of the usual form, supported upon an oscillating shaft, E'. Upright arms r and r' (see Fig. 3) are rigidly affixed to the shaft E', the former of which is bent backward and encircles the pendulum at its free extremity to actu-

ate the same, while the latter is provided with a cross-head, p, the purpose of which is hereinafter more particularly described.

That portion of the dial or surrounding surface of the clock-face which corresponds to the eyes of the object represented thereon is cut away to form openings m, and eyeballs G, pivoted as shown in Fig. 4, are pivotally supported behind the openings thus produced. A U-shaped piece of sheet metal, n, of the requisite size, having one arm longer than the other, is bent into the form shown, with its longer arm q' doubled under and backward upon itself, to afford a support for a vertical pivot, q', passed through bearings q toward the extremities of the arms. The pivots q' carry the eyeballs G, each having inserted in its rear side a pin, o, passed through a link, p', of the cross-head p, (hereinbefore mentioned,) whose reciprocating movement communicates a rolling motion through the pins o to the eyeballs.

The part n, forming the pivotal support for an eyeball G, may be affixed to any portion of the rear surface of the dial or clock-face, which will bring the eyeball properly and apparently within a socket, m, corresponding with the eye of a figure formed on the front surface of the dial or clock-face, and as many pairs of pivoted eyeballs may be provided as there are figures.

It is obvious that the object or objects to be actuated by the pendulum and the intervening mechanism are not, of necessity, eyeballs, inasmuch as any other feature or features of the figure represented could in a similar manner readily be made to move.

What I claim as new, and desire to secure by Letters Patent, is—

1. In a pendulum-clock, the combination, with the pendulum and face of the clock, having one or more openings, of an object pivotally supported behind each opening in the face and provided with an extension, o, an arm, r', supported on the shaft of the anchor-escapement to oscillate with the same, and having a link, p', carried by the arm r' and engaging with the extension o, and an arm, r, connecting the shaft of the anchor-escapement with the pendulum, substantially as and for the purpose set forth.

2. In a pendulum-clock, the combination of

the face provided with a figure and having openings for eyes, an arch-shaped projection, C, carrying the pendulum, eyeballs G, pivotally supported on the rear side of the clock-face, adjacent to the openings in the same, upon rigid U-shaped bearings n q, pins o, extending backward from the eyeballs, an arm, r', supported on the shaft of the anchor-escape-
5 ment to oscillate with the same, and having a cross-head, p, and links p', engaging with the

pins o, and an arm, r, connecting the shaft of the anchor-escapement with the pendulum, whereby the vibrations of the latter will move the eyeballs, substantially as and for the purpose set forth.

LEOPOLD FEUERSTEIN.

In presence of—
MASON BROSS,
WM. SADLER.
